UNITED STATES PATENT OFFICE.

CHARLES T. REDFIELD, OF GLENHAVEN, NEW YORK.

SAW.

SPECIFICATION forming part of Letters Patent No. 654,075, dated July 17, 1900.

Application filed April 18, 1900. Serial No. 13,326. (No model.)

To all whom it may concern:

Be it known that I, CHARLES T. REDFIELD, residing at Glenhaven, in the county of Cayuga and State of New York, have invented 5 certain new and useful improvements in Saws, of which the following is a specification.

My invention is an improvement in saws; and it consists in certain novel constructions and combinations of parts, as will be herein- 10 after described and claimed, whereby the frame of the saw will be given the desired firmness and rigidity when tightened for use.

In the drawings, Figure 1 is a side elevation, and Fig. 2 a top plan view, of my saw. 15 Fig. 3 is a detail cross-section on about line 3-3 of Fig. 1. Fig. 4 is a detail perspective view illustrating the means for tightening the saw-blade. Fig. 5 is a side view, partly broken away, of a somewhat-different construction 20 from that shown in Fig. 1; and Fig. 6 is a detail cross-section on about line 6-6 of Fig. 5.

The handle-bar A and the front bar B are provided at A' and B' with sockets for the ends of the arch and with mortises A² and B² 25 for the tenoned ends of the brace-bar, as shown in Fig. 1.

The arch-bar C is curved from end to end, rising at its center, and is provided at its ends with the tenons C', which fit in the sockets 30 A' and B', and the shoulders C² at the base of said tenons, which shoulders bear squarely against the handle and front bar.

The brace-bar D is straight from end to end, rests at its center squarely against the 35 crown of the arch-bar, is positively and firmly secured to the arch-bar at such center and crown, and is held at its ends positively to the handle A and front bar B by means of the pins E, which extend through the parts A and B and through the tenons D', formed at the 40 ends of the brace-bar B and fitted in the mortises A² and B², as will be understood from Figs. 1 and 2.

The central connection between the arch C 45 and the brace-bar D is preferably effected by means of a rivet I, which is passed upwardly through the arch-bar C, thence through the brace D, and riveted to unite the parts firmly together, as will be understood from Fig. 1. 50 I refer to the bar D as a "brace" because it serves such purpose not only with respect to the handle A and front bar B, but also with

respect to the arch C, as in the operation, more fully described hereinafter, the brace-bar prevents the said arch from moving upwardly at 55 its crown by reason of the direct tensile strain on the bar D, and such bar also prevents the arch from any forward or backward movement relative to the bar D and from any movement at its ends, thus preventing any racking 60 of the frame or any carrying down, up, or out of the said arch, preserving the arch and the bar D, together with the handle A and front bar B, in true alinement.

The ends of the handle A and bar B below 65 the arch C support the blade F, which connects said parts and is provided with means whereby it can be strained longitudinally. As shown, the blade F is pinned to the handle A at F' and is provided at its opposite end 70 with a bolt G, which is slit at G' to embrace the end of the blade F and is pivoted or riveted to said blade at G². This bolt G extends through an opening G³ in the bar B and receives the washer H' and the winged nut H, 75 by which the blade can be tightened in the frame to any desired degree.

In the operation of my invention it will be seen the bar D and arch C are secured positively together at their centers by the pin I, 80 thus connecting the said parts firmly together. The pins E are conveniently removable, as is the pin F', so the saw can be readily taken to pieces for convenience in shipment or storage. This, however, is merely incidental to 85 the invention, the main feature of which is the special construction described, whereby the frame of the saw is given the desired rigidity, as will be more fully described.

In Figs. 5 and 6 I illustrate a somewhat- 90 different construction, in which the arch and brace-bar are secured together at their middles by a cross-pin J and at their ends in connection with the handle and front bar in substantially the same manner as that shown 95 in Fig. 1; but the brace-bar K is of thin metal and fits in a groove or kerf K', cut in the crown of the arch and secured by the cross-pin J, as shown in the said figures.

When the parts are assembled, as shown 100 in Fig. 1, and the saw-blade is tightened by screwing up the nut H, the arch C will be compressed and will have a tendency to rise at its crown or center. The same movement

which gives the arch an upward tendency | operates by the leverage of the handle A and bar B, fulcruming at A' and B', to give a strong direct tensile strain upon the brace D, 5 which operates to counteract and resist the upward thrust of the arch, as will be readily understood. By pinning the brace D firmly to the arch at the center thereof I avoid any tendency of the arch to carry laterally out in 10 either direction and prevent any sliding movement of the arch relatively to the brace D. I also by this construction prevent any movement of the joints of the frame and so avoid any racking of the frame and preserve 15 all parts in true alinement at all times.

As before suggested, the bar D is made straight from end to end, so that the strain in tightening the blade F operates to give a direct longitudinal tensile strain to the bar D 20 in such manner as to firmly resist any upward movement at the crown of the arch-bar. It will also be noticed that I make a comparatively-broad flat bearing where the brace-bar bears upon the arch-bar, which greatly aids 25 the stability of the saw and which cannot be secured if the cross-bar D is bent or curved.

In assembling the saw-frame when the ends of the arch-bar are in their sockets and one end of the cross-bar is in its recess B² or A² 30 the other end of the cross-bar will rest slightly above and out of alinement with its recess. So such end of the bar D will have to be depressed slightly in order for it to enter its recess and be secured to the frame-bar. This 35 also increases the rigidity of the frame and enables the saw-blade to be properly tightened by a slight adjustment.

Manifestly the rivet I may be in the form of a bolt or nut, and the pin E may be in the 40 form of a rivet, screw, or bolt when desired.

It will be noticed that my saw-frame is entirely free of braces or obstructions above the bar D, thus greatly simplifying the saw,

cheapening the same, and at the same time providing a perfectly-solid frame in which to 45 tighten the blade.

Having thus described my invention, what I claim as new, and desire to secure by Letters Patent, is—

1. The saw herein described consisting of 50 the handle-bar, the front bar, the arch engaged at its ends with said handle-bar and front bar and arched upwardly between its ends, the brace-bar made straight from end to end and extended over the arch-bar and in 55 contact therewith at its middle, means securing the ends of the brace-bar positively to the bars of the frame, the pin extending vertically through the arch at the crown thereof and through the brace-bar and securing such 60 parts rigidly together at their middles, the saw-blade connecting the opposite frame-bars and means for straining or tightening said saw-blade substantially as set forth.

2. A saw comprising the opposite frame-bars, the arch-bar extended between and engaged at its ends with said frame-bars and curved upwardly from end to end, the continuous brace-bar overlying the arch-bar, made straight from end to end and rigid at 70 its center with the arch-bar at the crown of the latter, means for securing the brace-bar positively to the frame-bars at the ends of the brace-bar, the saw-blade, and means for straining or tightening the same, all substantially as described whereby the longitudinal tension exerted on the saw-blade operates longitudinally on the straight brace-bar to hold the arch-bar from moving up between the frame-bars and increases the rigidity of 75 80 the saw substantially as and for the purposes set forth.

CHARLES T. REDFIELD.
